UNITED STATES PATENT OFFICE

121,427

DESIGN FOR A PHONOGRAPH RECORD PLAYER

John B. Suomala, Haddonfield, N. J., assignor
to Radio Corporation of America, a corpora-
tion of Delaware

Application April 29, 1939, Serial No. 84,675

Term of patent 7 years

To all whom it may concern:

Be it known that I, John B. Suomala, a citizen
of the United States, residing at Haddonfield, in
the county of Camden and State of New Jersey,
have invented a new, original, and ornamental
Design for a Phonograph Record Player, of which
the following is a specification, reference being
had to the accompanying drawing, forming part
thereof.

Figure 1 is a top plan view of a phonograph
record player embodying my new design, and

Figure 2 is a side elevational view of the same.
The side opposite that shown in Figure 2 is
substantially the same as the side illustrated ex-
cept that the control knob does not appear.

I claim:

The ornamental design for a phonograph
record player, substantially as shown and de-
scribed.

JOHN B. SUOMALA.
